UNITED STATES PATENT OFFICE.

WILLIAM H. PAGE, OF NORWICH, CONNECTICUT, ASSIGNOR TO THE MAGEE FURNACE COMPANY, OF BOSTON, MASSACHUSETTS.

DESIGN FOR A SECTION FOR HOT-WATER HEATERS.

SPECIFICATION forming part of Design No. 30,105, dated January 31, 1899.

Application filed June 17, 1897. Serial No. 641,203. Term of patent 14 years.

To all whom it may concern:

Be it known that I, WILLIAM H. PAGE, a citizen of the United States, residing at Norwich, in the county of New London and State 5 of Connecticut, have invented and produced a new and original Design for a Section of a Hot-Water Heater, of which the following is a specification, reference being had to the accompanying drawings, forming a part thereof.

10 In the drawings, Figure 1 is a view in obverse perspective of my design, and Fig. 2 is a view in reverse perspective of the design.

As shown in the drawings, the leading or 15 material features of my design consist of the section A, having the grooved sides *a*, the oval columns B, separated by spaces *b*, the box C, to which the oval columns extend, the square

columns D, rising from the box to the top section E, and all extending from the side F, having the downward extension *f*. The inner 20 face of the extension may be provided with small knobs or points, if desired. The top section is rounded at one corner and cut away at the other corner, as shown.

Having thus fully described my invention, 25 I claim and desire to secure by Letters Patent of the United States—

The design for a section of a hot-water heater, as herein shown and described.

WILLIAM H. PAGE.
